UNITED STATES PATENT OFFICE.

CHARLES H. HUNT, OF LAWRENCE, MASSACHUSETTS.

THROSTLE SPINNING-MACHINE.

Specification forming part of Letters Patent No. 9,283, dated September 28, 1852; Reissued May 17, 1864, No. 1,672.

To all whom it may concern:

Be it known that I, CHARLES H. HUNT, of Lawrence, in the county of Essex and State of Massachusetts, have invented a new 5 and useful improvement in that part of the mechanism of a throstle spinning-machine by which the vertical movements of the spindle are regulated or produced in order to lay the yarn in the proper manner on the bobbin; and I do hereby declare that the same 10 is fully described and represented in the following specification and the accompanying drawings, letters, figures, and references thereof.

15 Of the said drawings Figure 1 denotes a top view, Fig. 2 a front side elevation, and Fig. 3 an end elevation of a throstle frame containing my improvement.

In the said drawings only one spindle and 20 its flier are represented as applied to each of the sides of the frame, it being understood that the spindle and flier rails of each side are to be supplied with any number of such as may be required.

25 A (Figs. 1, 2, and 3) is the stationary flier rail, B the movable spindle rail, C the flier, D the spindle, E, E, the stationary guide rods of the spindle rail. The said spindle rail is supported by two chains F, F, 30 that are attached to it and respectively pass over two pulleys G, G, that are placed in arms H, H, that extend upward from the horizontal rail a of the frame I. These chains are respectively attached to the ends 35 of long rods or bars c, c, that have chains d, d, connected to their opposite ends, the said chains d, d, being wound around and attached to a horizontal shaft K, as seen in Fig. 4, which denotes a cross section of the 40 shaft and shows the chain and the arc or semicircular link e thereof, that is employed to extend partly around the shaft when the chain is quite wound up. Each spindle rail has two of these chains extending from the 45 shaft K.

In the process of laying the yarn on the bobbin the shaft K is not only to have a regular, reciprocating, rotary, movement imparted to it such as will lower and raise 50 the spindle rail, but between each two of such movements it is to be turned a little so as to unwind the chains from it in order to let the spindle rail drop a short distance, in order that the building up of the yarn 55 on the bobbin may gradually take place.

The mechanism that constitutes my improvement is to effect such movements, and is as follows:

A gear wheel L is fixed on the shaft K and made to engage with a pinion M that 60 is firmly fastened on the inner end of a horizontal shaft N, see Fig. 1 and Fig. 5, which is a vertical section taken through and in line of the axis of the shaft N. On the shaft N are two wheels O, P, which run or 65 turn freely on it. The inner of these wheels, viz, the wheel O, has a small ratchet wheel R affixed to its inner side, which ratchet wheel works in connection with a spring click S that is fastened to the periphery of 70 a wheel T, that is fastened to and on the shaft N, the whole being shown in Fig. 6, which is an inner side view of the wheel O. The said wheel O is made with ratchet teeth f around its periphery and with a 75 row g of pins extended from its inner side, as seen in the drawings, there being the same number of pins or their equivalents as ratchet teeth f.

An escapement lever formed of an arm h 80 and two pallets i, k, arranged with respect to one another, as seen in the drawings, is made to rock on a fulcrum l that projects from the wheel P and over the periphery of the wheel O. One of the pallets (viz. i) 85 of this escapement lever operates in connection with the ratchet teeth of the wheel O, while the other pallet (viz. k) operates in connection with the row of pins that extend from the side of such wheel O. 90

The outer face of the wheel P has two concentric circular grooves or paths m, n, made in it, each of which is made by means of a semicircular groove to run into the other at their ends, as seen in Fig. 7, which 95 is a side view of the wheel. Between these grooves there is a concentric row of pins o, o, arranged at equal distances apart, and so as to engage with a toothed pinion p, that is fixed on a shaft q, that is supported on the lower end of a pendulous or vibrating arm r, that is hung on a shaft s, suitably supported at the upper part of the frame of the machine. There is a pulley t fixed on the shaft q, and another one (u) fixed on 105 the shaft s, an endless belt v being made to pass around the said pulleys. By putting the pulley u and its shaft s in revolution by any suitable means while the throstle frame is in action, the pinion p will be put 110

in rotation, and as the inner end of its shaft is inserted in the path formed by the concentric grooves m, n , and their joining semi-circular grooves, the pinion will so act on 5 the rows of pins o, o , as to produce a reciprocating rotary movement of the wheel P . When the wheel P is moved in a direction such as will press the pallet i of the escapement lever against the next adjacent ratchet 10 tooth of the wheel O , such wheel O will be put in rotation and will continue so until the arm h of the escapement comes into contact with a stationary stud or pin y arranged as seen in the drawings. The pressure 15 of the arm against the stud causes the pallet i to rise to the top and above the tooth or escape over it in a manner similar to that in which the pallet of an escapement of a pendulum escapes over a tooth of its 20 toothed wheel. The two pallets i, k , act on the rows of ratchet teeth and pins on the wheel O , very, if not essentially, like the pallets of a common pendulum escapement, so that at the next time the escapement 25 is moved in a direction toward the stud y , it will pass and act against that tooth next to the one it last slipped over. The said slipping by a tooth of the wheel O , allows the shaft K to turn a little, so as 30 to allow the spindle rail or rails to drop a short distance in order to increase the up-

ward wind of the yarn on the bobbin or lower the bobbin a little in order that the yarn may be wound higher up on it. By putting a crank on the outer end of the shaft N and turning it in the right direction or that denoted by the arrow x , we cause the chains of the shaft K to be wound up thereon so as to elevate the spindle rails to their highest positions, preparatory to 40 the operation of spinning on another set of bobbins.

What I claim as my invention is—

The escapement wheel O , its escapement lever (composed of the arm h and pallets i, k) and stud y , in combination with the reciprocating rotary mechanism, composed of the wheel P , its concentric and endless grooves, row of pins, the pinion p , and pendulous bar or arm r , the whole being 45 applied to give motion to the shaft N , its pinion, the gear of the shaft K , and the said shaft K , in order to effect the movements of the spindle rail or rails, essentially as 50 above specified.

In testimony whereof I have hereto set my signature, this eleventh day of May, 55 A. D. 1852.

CHARLES H. HUNT.
